UNITED STATES PATENT OFFICE.

WILLIAM A. LORENZ, OF HARTFORD, CONNECTICUT, ASSIGNOR TO THE OTAKA FABRIC COMPANY, OF HARTFORD, CONNECTICUT, A CORPORATION OF CONNECTICUT.

WALL PAPER.

Application filed January 4, 1921. Serial No. 434,940.

To all whom it may concern:

Be it known that I, WILLIAM A. LORENZ, a citizen of the United States, residing in Hartford, in the county of Hartford and 5 State of Connecticut, have invented certain new and useful Improvements in Wall Paper, of which the following is a specification.

This invention relates to crinkled paper and more particularly to the class of wall-papers, and one of its main objects is to produce a paper of this class having an improved appearance and a greater attractiveness than previous wall-papers, and also to overcome the difficulty of mismatching 13 of designs of adjoining strips as they are placed on the wall. This mismatching is sometimes due to atmospheric conditions, or to unequal expansion of the paper from the moisture of the paste.

20 According to the present improvements the paper is crinkled or corrugated in transverse lines so that it is stretchable longitudinally, and hence any designs printed or embossed upon the strips of paper may 25 be made to match one another accurately, by stretching the paper more or less as it is being applied to the wall. The defects in matching, due to imperfections of printing of the paper or to uneven expansion 30 thereof by dampness, are thus readily overcome. The crinkling of the paper also softens its appearance, or tends to avoid the harshness and glaring effect of ordinary wall-paper.

35 Other features and advantages will herein appear.

The accompanying drawing represents two strips of the improved paper, one of which has been pasted to the wall and the 40 other of which is about to be pasted.

The wall-paper is transversely crinkled or finely corrugated as at 11, whereby it is gathered and hence made stretchable longitudinally, and is also given an attractive 45 soft appearance. The design of the paper may also, if desired, include parallel longitudinal stripes 12, each comprising a succession of raised or embossed parallel beadings or oblong figures 13, these being separated by depressions 14, so that the paper is in effect corrugated in these stripes, and hence stretchable longitudinally. The crinkled paper may also be otherwise embossed with figures and designs, and its use 50 is not limited to wall coverings. The paper

is also preferably provided with main printed designs 15, which in this instance are intended to range horizontally along the wall. One strip 16 of the paper has been pasted on the wall 17 between a top molding 18 and a baseboard 19; and the second strip 20 is about to be applied to the wall. This second strip is shown purposely as mismatched with strip 16, the difference in the stretching of the two strips being indicated by 60 the blank space between the bottom of strip 20 and the baseboard 19. In order to make the two strips 16, 20 match perfectly, it is only necessary to stretch the paper down until the gap at 21 is closed up. This position may be maintained while the paper becomes adherent to the wall. In practice, the first strip applied to the wall may be stretched a little, and the remaining strips 65 may be stretched to correspond.

Variations may be resorted to within the scope of the invention, and portions of the improvements may be used without others.

Having thus described my invention, I claim:

1. A longitudinally stretchable wall paper having designs printed thereon and capable of being stretched to cause the designs on one strip to match those on an adjoining strip, said paper being transversely crinkled or corrugated to permit the necessary stretching.

2. A longitudinally stretchable wall paper having designs printed thereon and capable of being stretched to cause the designs on one strip to match those on an adjoining strip, said paper being transversely crinkled or corrugated to permit the necessary stretching, and being also provided with embossed designs.

3. A longitudinally stretchable wall paper having designs printed thereon and capable of being stretched to cause the designs on one strip to match those on an adjoining strip, said paper being transversely crinkled or corrugated to permit the necessary stretching, and being also provided with embossed designs, said embossed designs having a stripe arrangement, to permit stretching of the paper along the stripes 105 as well as along the body portions thereof.

WILLIAM A. LORENZ.
